Rudolf Einbigler,
Frank L. Pfe.

UNITED STATES PATENT OFFICE.

RUDOLF EINBIGLER, OF NEW YORK, N. Y.

VISUAL SIGNALING APPARATUS.

SPECIFICATION forming part of Letters Patent No. 247,323, dated September 20, 1881.

Application filed June 24, 1881. (No model.)

To all whom it may concern:

Be it known that I, RUDOLF EINBIGLER, a subject of the Empire of Brazil, residing in the city, county, and State of New York, have invented certain new and useful Improvements in Visual Signaling Apparatus, of which the following is a specification.

My invention relates to that class of apparatus for producing or exhibiting visual signals by the action of an electric current upon an electro magnet or magnets which are known as "annunciators." It more particularly relates to that class of apparatus which is designed to display or conceal signals which are intended to be visible at a considerable distance, and also to signals such as are employed on railroads to exhibit or conceal a light for use at night, or a number, letter, or other character or a color during the day.

The object of my invention is to so construct the operating mechanism of a visual signal that a given electric power may be made to operate a much larger signal than has been possible in visual signals heretofore in use, while at the same time the mechanism will occupy less space and be more simple and economical in its construction.

The subject-matter claimed will be hereinafter specifically designated.

The accompanying drawings illustrate an apparatus constructed in accordance with my invention in the best way now known to me, in which—

Figure 1 represents a plan view of the apparatus with a diagram of the circuit-connections; Fig. 2, a side elevation with part of the supporting-frame removed; Fig. 3, a front elevation of the apparatus in a position concealing the signal; and Fig. 4 shows the signal as it appears when displayed or exhibited.

In the drawings, A B represent two straight electro-magnets, each of which consists of a single coil of wire enveloping an iron core, the projecting ends of which cores a b c d are provided with soft-iron extension or pole pieces a' b' c' d', which are of a length exceeding the diameter of the coils of the electro-magnets. These pole-pieces are fastened to the supporting-frames C C' by the screws a² b² c² d², which extend through the supporting-frame and pole-pieces and into the cores of the electro-magnets.

nets, and thus firmly hold the electro-magnets and pole-pieces together and to the frames C C'. These supporting-frames should be constructed of brass or other non-magnetic metal, so as to allow of no magnetic connection between the poles of the electro-magnets. The pole-pieces a' b' c' d' are preferably constructed in the form of a trapezium, as best seen in Fig. 2, in order to more conveniently actuate the armatures, as hereinafter explained.

Three soft-iron armatures, D, E, and F, are employed, which are mechanically linked together into a single system. These armatures are parallel to the axes of the electro-magnets and at right angles to the pole-pieces. The armatures D and E have their axes of oscillation parallel to the axes of the coils of the electro-magnets, so that the ends of both pole-pieces can freely act on their respective armatures. A third soft-iron armature, F, is mounted between the pole-pieces of the respective electro-magnets, and is pivoted at its upper corners to the frames C and C', as shown at h, and, like the armatures D and E, has its axis of oscillation parallel with the axes of the coils of both electro-magnets. This armature, being placed between and close to the pole-pieces of each electro-magnet, is, of course, within the common magnetic field of both. The armatures D, E, and F, being respectively pivoted to the frames C and C', as described, are joined together by connecting rods or links i i', pivoted to them, preferably in the middle of their lengths. Hence all the armatures form a single system, and will be simultaneously moved by the action upon them of either of the electro-magnets A B. An upright arm, g, is rigidly attached, preferably, to the central armature, F. A horizontal finger, g', is joined to the upper extremity of the arm g, and preferably at right angles to the same when in a perpendicular position, which extends through a hole in the base-board or support H, in order to actuate the signaling mechanism, which will now be described.

Referring to Fig. 4, G represents a plate of sheet metal, which may be of any convenient size, which is permanently secured to a board or other support, H, and bears the lower half of a designating number, letter, word, or other character. Another plate, G', of the same di-

mensions as the plate G, is hinged at its lower edge to the upper edge of plate G, and this bears the upper or remaining half of the designating-character. Thus if the plate G' be 5 folded back so that it is parallel with the support H, it will expose the upper, and the plate G the lower, portion of the designating-character, which, in the figure, is the number 15, while if the plate G' be folded down so that its 10 upper edge is coincident with the lower edge of the plate G, it will completely cover up and conceal the character. A counter-balance, w, is secured to the lower or hinged edge of the plate G', which should be of such weight that if the 15 plate G' be placed in a position of about eighty-five degrees from a horizontal plane, the plate and weight will be in a condition of unstable equilibrium. An aperture, w', in the base or support H allows the weight w to freely pass 20 through in moving from one position to the other.

The operation of my improved signal apparatus is as follows: If a current of electricity be sent through the coil of electro-magnet A, 25 magnetizing its core and pole-pieces a' b', the armature D, being pivoted at its lower edge, will be drawn toward the upper edge of the poles a' b', and the armature F, on the opposite side of said poles, being pivoted at its upper 30 edge, will be drawn toward the lower edge of the opposite side of said poles. This movement of the armatures is communicated to the upright arm g, which carries with it the finger g', causing the projection g² to strike the counter-balance w with sufficient force to turn it into 35 a position to overbalance the plate G', to which it is attached, in consequence of which it falls into the aperture w', bringing the plate into an upright position, its upper edge resting 40 against the upper portion of the support H, as shown in Fig. 3, and exhibiting the signal. If, now, it is desired to return the signal-plate G' to a position for concealing the signal, a current of electricity is transmitted 45 through the coil of the other electro-magnet, B, magnetizing its core and pole-pieces c' and d', and attracting the armature F toward the lower edge of the pole-pieces c' and d', and at the same time the armature E toward the upper 50 edge of the pole-pieces d' and c' on the opposite side from the armature F, being the reverse of the operation hereinbefore described. The finger g' is thus caused to strike against the plate G' with sufficient force to cause it to 55 overbalance the weight w and descend into the position shown in Fig. 3, thus concealing the signal, while the weight returns to its upright position, in which it occupies the upper part of the aperture w'. The plate G' and weight 60 w will remain in this position until again actuated by the agency of electro-magnet A, as hereinbefore described.

I will now describe the circuits for operating the electro-magnets A and B.

65 One of the terminals of the coil of each electro-magnet is connected with one pole of a battery, P, either through the ground or by a

wire which is connected with said battery, which latter I have shown in diagram in connection with Fig. 1. The wire 1 connects the 70 terminals of electro-magnets A and B with battery P.

The circuit-closer which I prefer to employ is also shown in connection with Fig. 1, and consists of a spring or resilient strip of metal, 75 j, securely fixed at its upper end to a support, J, which may consist of a board, wall, or panel, or any object to which the same can be conveniently attached. Attached to the support J are two metallic contact-points, k k', placed 80 on either side of the free end of the metallic strip j, as shown, to which are attached the wires 4 and 3, respectively leading to the remaining terminals of the coils of electro-magnets B and A. A spindle or rod, L, having 85 a knob, l, at its outer extremity, is arranged to slide to and fro through a socket, K, attached to the support J, and is formed into a shifting yoke at its inner end, as shown in section in the figure. The spring j extends through said 90 yoke so that each end of the latter forms a stop, m n, therefor. By drawing the knob l outward the spring j is forced by the stop m toward the support J, and comes in contact with the point k', thereby closing the circuit 95 and transmitting a current from the positive pole of the battery P, through wire 2, spring J, contact-point k', wire 3, coil of electro-magnet A, (thus magnetizing its core and pole-pieces,) and wire 1, to the negative pole of the 100 battery, while, on the contrary, if the knob l be pushed inward toward the support J, the spring j is brought in contact with the point k by the pressure of stop n, and the current is transmitted from the positive pole of battery P, 105 through wire 2, spring j, contact-point k, wire 4, coil of electro-magnet B, (magnetizing its core and pole-pieces,) and wire 1, to the negative pole of the 110 battery. Thus if it is desired to exhibit the signal hereinbefore described, the spring j is brought in contact with point k' by pulling the knob l outward, which closes the circuit and transmits the current through electro-magnet A, as described, magnetizing its core and pole-pieces, which by the operation hereinbefore described places the plate G' 115 in an upright position and exhibits the signal. If it is desired to conceal the signal, the knob l is pushed inward toward the support J, pressing the spring j against the contact-point k, 120 which closes the circuit and magnetizes the core and pole-pieces of electro-magnet B, which by the means hereinbefore explained conceals the signal.

By an obvious modification of the apparatus described it may be made use of with advantage as a signal to exhibit or conceal a lamp for use on railroads, or in other places where it is desirable to employ a light as a signal. This may be done by constructing the support H partly of glass and arranging it to accommodate any suitable lighting apparatus which it may be desirable to conceal or exhibit by means of the plate G'. In this case it would 125 130

be preferable to make use of two weights projecting from the outer ends of the plate G', instead of the single one shown in the drawings, so that they will not occupy any space 5 within the glass signal.

It is obvious that many modifications may be made in my invention without departing from the principle thereof. For instance, there may be a series of several electro-magnets with 10 their armatures, instead of the two shown, which would probably be advantageous, if it is desirable to operate a very large or heavy signal-plate.

I claim as my invention—

- 15 1. The combination, substantially as herein-before set forth, of two electro-magnets, each consisting of a single coil of wire enveloping an iron core, three armatures whose axes of oscillation are parallel to the axes of said coils, 20 one of said armatures being between the respective poles and within the magnetic field of both of said electro-magnets, and one or more connecting rods or links uniting said armatures.
- 25 2. The combination, substantially as herein-before set forth, of two electro-magnets, each consisting of a single coil of wire enveloping an iron core, three armatures whose axes of oscillation are parallel to the axes of said coils, 30 one of said armatures being between the poles and within the magnetic field of both of said electro-magnets, one or more connecting rods or links uniting said armatures, and mechanism, substantially such as described, for actuating a visual signal.
- 35 3. In a signaling apparatus, the combination, substantially as herein-before set forth, of a concealing or exhibiting plate hinged at one of its edges, and a counter-balance attached to or 40 near the hinged edge of said plate, whereby the

plate is maintained in a position to either conceal or exhibit a signal.

4. The combination, substantially as herein-before set forth, of two electro-magnets, each consisting of a single coil of wire enveloping 45 an iron core, three armatures whose axes of oscillation are parallel to the axes of said coils, one of said armatures being between the respective poles and within the magnetic field of both of said electro-magnets, one or more 50 connecting rods or links uniting said armatures, an arm or rod attached to said connecting-rods, a hook or finger attached thereto, and a visual signal actuated by the movements of said finger, provided with a concealing or 55 exhibiting plate hinged at one edge, and having a counter-balance attached to or near the hinged edge of said plate.

5. The combination, substantially as herein-before set forth, of the circuit-wires, their two 60 insulated contact-points, the interposed contact-spring, and the shifting yoke embracing the spring to control its electrical connection with either of said insulated contact-points.

6. The combination, substantially as herein-before set forth, of the two electro-magnets, circuit-wires respectively connecting said electro-magnets with two insulated contact-points, the interposed contact-spring, and the shifting yoke embracing the spring to control its electrical connection with either of the said insulated contact-points and the electro-magnet connected therewith.

In testimony whereof I have hereunto set my hand this 21st day of May, A. D. 1881.

RUDOLF EINBIGLER.
